(57) **CLAIM**

The ornamental design for a robotic pool cleaner, as shown and described.

DESCRIPTION

FIG. 2.1 is a first perspective view of a robotic pool cleaner, showing our new design.

FIG. 2.2 is a second perspective view of the robotic pool cleaner thereof.

FIG. 2.3 is a front view of the robotic pool cleaner thereof.

FIG. 2.4 is a back view of the robotic pool cleaner thereof.

FIG. 2.5 is a left view of the robotic pool cleaner thereof.

FIG. 2.6 is a right view of the robotic pool cleaner thereof.

FIG. 2.7 is a top view of the robotic pool cleaner thereof, according to the disclosed subject matter.

FIG. 2.8 is a bottom view of the robotic pool cleaner thereof.
